CLAIM

The ornamental design for a display screen or portion thereof with graphical user interface, as shown and described.

DESCRIPTION

The sole FIGURE is a front view of a display screen or portion thereof with graphical user interface showing the claimed design. The dot-dot broken line is part of the claimed design. The dash-dash broken lines form no part of the claimed design.

The dot-dot broken line is part of the claimed design. The dash-dash broken lines in the FIGURE show the display screen or portion thereof with graphical user interface that forms no part of the claimed design.
